UNITED STATES PATENT OFFICE.

CHARLES BRUDERLEIN, OF NEW YORK, N. Y.

WOODWORKING-MACHINE.

No. 911,200.

Specification of Letters Patent.

Patented Feb. 2, 1909.

Application filed November 4, 1907. Serial No. 400,446.

To all whom it may concern:

Be it known that I, CHARLES BRUDERLEIN, a citizen of the United States, and residing at New York, in the county of New York and State of New York, have invented certain new and useful Improvements in Woodworking-Machines, of which the following is a specification, such as will enable those skilled in the art to which it appertains to 10 make and use the same.

This invention relates to wood-working machines of the class known as tenon cutters; and the object thereof is to provide an improved machine of this class particularly 15 designed for making lock corners for boxes, crates and other receptacles, also miter corners or joints, and which also may be employed for making tongue and groove joints or various other kinds and classes, all of 20 such joints being what are known as lock joints.

The invention is fully disclosed in the following specification of which the accompanying drawings form a part, in which the 25 separate parts of my improvement are designated by suitable reference characters in each of the views, and in which:—

Figure 1 is a left side view of my improved machine, Fig. 2 a back view thereof,

Fig. 3 a partial section on the line 3, 3 of Fig. 2, Fig. 4 a similar section on the line 4, 4 of Fig. 2, Fig. 5 a partial front view of the top portion of the machine and showing the preferred form of construction, Fig. 6

a view similar to Fig. 5, but showing a modification, Fig. 5^a an end and side view of a piece of board, the end of which is provided with tongues and grooves made by the machine assembled as shown in Figs. 1, 2 and 5,

Fig. 6^a an end and side view of a piece of a board provided with tongues and grooves made by the machine assembled as in Figs. 1, 2 and 6. Fig. 7 a section on the line 7, 7 of

Fig. 6, Fig. 8 a perspective front view of a gage which I employ. Fig. 9 a perspective view of a corner formed from two boards similar to that shown in Fig. 5^a. Fig. 10 a plan view showing two pieces of boards joined together longitudinally by tongue and

groove locking devices made by my improved machine, and;—Fig. 11 a plan view of a miter joint, the separate parts of which are joined together by tongue and groove de-

vices made by my improved machine.

In the practice of my invention I provide

a main frame comprising a base a , and two upright side members a^2 , and in the bottom portion of which are supports a^3 in which is mounted a forwardly and backwardly arranged shaft a^4 provided at its front end with a beveled gear a^5 , and at its rear end with a larger beveled gear a^6 and between said gears a^5 and a^6 is a gear a^7 smaller than either of the first named gears, and the gears a^6 and a^7 are movable longitudinally of the shaft a^4 . These gears are provided with hubs a^8 , and a yoke b is connected with said hub, and a pin b^2 is connected with said yoke for forming a handle by which it may be moved forwardly and backwardly, in which operation the gears a^6 and a^7 are moved longitudinally of the shaft a^4 , and the pin b^2 passes outwardly through the left side frame member a^2 , as shown in Fig. 4, and pivoted to said frame member at b^3 is a lock arm b^4 having notches or recesses b^5 in the bottom side thereof adapted to receive the pin b^2 and hold it in the desired position, and connected with the arm b^4 is a spring b^6 which is secured to the said left frame member a^2 at b^7 , and the spring b^6 causes the lock arm b^4 to bear firmly on the pin b^2 and hold it in the desired position, in the operation of the machine.

In the right side of the bottom portion of the machine is mounted a shaft c , which ranges at right angles to the shaft a^4 , and the shaft c is provided with two similar beveled gears c^2 and c^3 , the first of which operates in connection with the gear a^7 on the shaft a^4 , and the second of which operates in connection with the gear a^6 on the shaft a^4 , and said shaft c is also provided with a drive wheel c^4 of the sprocket, or any other suitable type.

The side frame members a^2 are connected by tie rods c^5 and c^6 , in the form of construction shown, and in the bottom portion of the frame is a downwardly and backwardly directed chute c^7 . Mounted in the top portion of the frame and, in the form of construction shown, slightly forwardly of the shaft a , and parallel therewith is a main cutter and drive shaft d , provided at its right end with a belt wheel d^2 by which it may be driven, or said shaft may be driven by a crank or in any desired manner. The shaft d is also provided over the drive wheel c^4 with a drive wheel d^3 of smaller dimensions than the wheel c^4 and mounted

on said wheels is a drive chain d^4 . Mounted on the shaft d is a cone shaped cutter e , composed of equally spaced disks e^2 provided with cutting teeth e^3 somewhat similar in form to saw teeth, and the cutter disks e^2 increase in size from the left to the right side of the machine. The right upright member a^2 of the frame is provided with a forwardly directed extension d^5 which is inclined inwardly as shown in Fig. 3, and mounted in the front of the part d^5 and the left side member a^2 of the frame is a vertically movable slide f connected with the parts d^5 and a^2 by a tongue and groove construction as shown at f^1 in said figure. The slide f is provided at its bottom with a base member f^2 , and connected with the base of the frame is a yoke-shaped device f^3 , and connected with the base or bottom f^2 of the slide f is a screw shaft f^4 which passes downwardly through the top of the yoke-shaped device f^3 , and said shaft is provided within said device with a beveled gear f^5 which meshes with the gear a^3 on the shaft a^4 , and the beveled gear f^5 is threaded interiorly to correspond with the thread on the shaft f^4 , and the turning of the gear on the shaft f^4 will feed said shaft, and the slide f up or down according to the direction in which the nut f^6 is turned.

The slide f in addition to the base f^2 is composed of vertically arranged side members f^6 , vertical top guides f^7 and a top cross head f^8 , together with side gages g connected with the side pieces f^6 are adjustable laterally, said side gages being provided with transverse slots g^2 through which are passed screws g^3 , and the gages g are provided at their inner edges with forwardly directed members g^4 , and passing vertically through the cross head f^8 at the top of the slide is a screw g^5 , on the lower end portion of which is mounted a jaw carrying head g^6 , the counter-part of which is the base f^2 of the slide f which also constitutes a jaw carrying head, and by turning the screw g^5 the jaw carrying head g^6 may be raised and lowered as will be readily understood.

Mounted in the top of the frame is a transverse gage supporting plate h , which carries a gage h^2 , said gage being provided with forwardly and backwardly arranged slots h^3 , through which are passed screws h^4 by which the gage h^2 is secured to the plate h , and said gage h^2 is provided at its front edge with depending fingers h^5 , as clearly shown in Figs. 2, 3 and 8.

The support plate h is provided at its rear edge with an upwardly directed lug h^6 through which is passed a screw h^7 which enters the rear edge of the gage h^2 , and by means of which said gage may be adjusted forwardly and backwardly. In the preferred form of my construction, the jaw

carrying head g^6 on the screw g^5 is provided with a detachable jaw i which is substantially triangular in form when viewed from the front, and said jaw is connected with the head j^6 by a tongue and groove device 70 as shown at i^2 . The jaw carrying head f^2 , or base of the slide f , is provided with a detachable jaw j which is substantially triangular in form and which is detachably connected with said jaw carrying head f^2 by 75 a tongue and groove construction as shown at j^2 , and when these jaws are in position as shown in Fig. 5, the bottom surface of the jaw i is inclined upwardly and to the right, while the top surface of the jaw j is inclined 80 downwardly and to the left.

In Fig. 5 of the drawing I have shown at k a number of pieces of boards which are placed between the jaws i and j , and the ends of which are to be provided 85 with tongues and grooves to form inter-locking corner joints, and in practice it is necessary before placing the boards k in position to raise the slide f so that the bottom board, or that next to the jaw j , when said boards 90 are inserted into position, will clear the teeth of the cutting disks e^2 , and this position of said boards is regulated by the fingers h^5 of the gage h^2 . The slide f is raised by throwing the pin b^2 of the yoke 95 b into the position shown in Fig. 1, in which position the gears a^7 and c^2 on the shafts a^4 and c will mesh, and then turning the shaft d or applying the power thereto. When the slide f has been raised to the desired point 100 the boards k are placed in position and the jaw i is moved down so as to press said boards tightly between said jaw and the jaw j . The yoke b and pin b^2 are moved forwardly so as to throw the gear a^6 on the 105 shaft a^4 in connection with the gear c^3 on the shaft c . This operation will reverse the direction of the gear f^5 on the vertical screw f^4 , and when the power shaft d is turned the slide f will be lowered and in this operation the cutter disks d^2 are also rotated and the direction of this rotation is in the direction of the curve of teeth e^3 on said disks. During this operation the slide f is gradually lowered and the boards k are provided 110 in the ends thereof with tongues h^2 and grooves h^3 as shown in Fig. 5^a. It will be observed that these tongues and grooves are cut at an inclined angle to the longitudinal center line of said boards, and also at an 115 inclination to the plane of the boards and the form of interlocking corner shown in Fig. 9 is thus formed.

Instead of using the triangular jaws i and j shown in Fig. 5, other jaws m and m^2 125 may be substituted therefor, as shown in Fig. 6, and the operation of the machine with these forms of jaws will be the same as when the jaws i and j are employed, but the form of the tongues and grooves produced 130

in the ends of the boards when the jaws m and m^2 are employed will be as shown in Fig. 6^a and an inter-locking corner similar to that shown in Fig. 9 may thus be produced, but the tongues and grooves produced in this manner, as shown in Fig. 6^a, are not cut at an angle to the plane of the boards, but are cut at an angle to the longitudinal central line of the boards.

10 It is possible, by means of my machine, to produce a joint similar to that shown in Fig. 10, in which two pieces of boards are connected in the same plane, and the opposite edges thereof made parallel, or two pieces 15 of boards may be connected in the same plane without the opposite edges thereof being parallel; for if desired two pieces of boards may be connected as shown in Fig. 11 to form an ordinary miter joint. It 20 will be understood, of course, that the character of the connections or joints is determined by the manner in which the boards are inserted into the machine and the position in which the boards are held. The vertically arranged gages g on the slide f are 25 adjustable laterally and said gages may be adjusted so as to permit the boards k to be inserted at right angles to the shaft d instead of at an acute angle thereto, as when 30 the slide f and gages g^2 are in the position shown in Fig. 3.

The gage h^2 in the top back portion of the machine, or the fingers h^5 thereof limit the extent to which the boards k are inserted, and in this manner serve to limit the depth of the tongues and grooves formed in the ends of the boards, and it will be understood that at the beginning of the 35 operation of cutting the tongues and grooves the slide f must be at such height that the boards k or the rear ends thereof will be over the front portions of the cutter disks e^2 and as the slide f descends the ends of the boards k are thrown into contact with 40 the teeth of said cutter disks.

In the operation of the machine as hereinbefore described, the dust or cuttings produced by the cutter disks e^2 fall into the chute c^7 and are discharged at the back of the 45 machine, and thus kept from falling into the gearing at the bottom of the main frame.

It will be understood of course that the shaft d which constitutes the cutter shaft is in fact the main shaft of the machine, and 55 the shafts c and a^4 in the bottom portion of the machine are supplemental and auxiliary shafts, they and their connected gearing being operated by the shaft d through the drive chain d^4 to turn the vertically arranged shaft f^4 so as to operate the vertically movable slide f .

My machine, as shown and described, is capable of forming inter-locking tongue and groove box corners, inter-locking miter 60 tongue and groove corners, and various other

forms of lock joints, one of which is shown in Fig. 10; and while I have shown and described the preferred construction of my invention it will be apparent that various changes in the details may be made, within 70 the scope of the appended claims, without departing from the spirit of my invention or sacrificing its advantages.

Having fully described my invention, what I claim as new and desire to secure by Letters 75 Patent, is;—

1. In a machine of the class described, a frame, a horizontal cutter shaft mounted in the top portion thereof and provided with a cone-shaped cutter composed of separate 80 equally spaced disks having cutting teeth, a vertically movable slide mounted in front of said cutter and at a lateral angle thereto equal to the angle of the cutting teeth on the cutter disks to the shaft on which said disks 85 are mounted, said slide being adapted to hold material to be acted upon, a gage mounted in the top of the frame above the cutter and provided with depending fingers which pass downwardly back of said slide 90 between said cutter disks, said fingers ranging at an angle to the cutter shaft similar to that of said slide, means for clamping material to be operated upon in said slide, means for rotating said cutter shaft and cutter, and means for giving said slide a continuous upward or downward movement, comprising a vertically arranged screw shaft connected with the bottom of said slide and adapted to move it vertically, a beveled gear 100 mounted on the lower end portion of said shaft, a horizontal shaft mounted in the bottom of the frame and provided with a beveled gear which operates in connection with the beveled gear on the screw shaft, said 105 horizontal shaft being provided with two beveled gear wheels which are movable longitudinally thereon, a supplemental horizontal shaft provided with two beveled gear wheels operating in connection with the beveled gear 110 wheels which are movable on the last named shaft, and means for gearing the horizontal shaft and the cutter shaft in connection.

2. In a machine of the class described, a frame, a horizontal cutter shaft mounted in the top portion thereof and provided with a cone-shaped cutter composed of separate 115 equally spaced disks having cutting teeth, a vertically movable slide mounted in front of said cutter and at a lateral angle thereto 120 equal to the angle of the cutting teeth on the cutter disks to the shaft on which said disks are mounted, said slide being adapted to hold material to be acted upon, a gage mounted in the top of the frame above the cutter and 125 provided with depending fingers which pass downwardly back of said slide and between said cutter disks, said fingers ranging at an angle to the cutter shaft similar to that of said slide, means for clamping material to 130

be operated upon in said slide, a vertically arranged screw connected with the bottom of said slide and adapted to give the same a continuous upward or downward movement, 5 and devices in operative connection with the cutter shaft and said screw for turning the latter in either direction when said cutter shaft is operated.

In testimony that I claim the foregoing as my invention I have signed my name in presence of the subscribing witnesses this 2nd day of November 1907.

CHARLES BRUDERLEIN.
